MANUFACTURING COMPANY, OF WHITTIER, CALIFORNIA, A CORPORATION OF
CALIFORNIA

CORE BARREL

Application filed November 4, 1926. Serial No. 146,093.

My invention relates to the oil well drilling industry and is particularly directed to core obtaining devices.

I have found that in order to be sure of obtaining an integral core it is necessary that the core drill produce a straight hole. If a crooked hole is drilled by the core drill, it is likely that the upper end of the core being formed will engage the side of the barrel, this placing side strain on the core and usually resulting in its breakage. It is also necessary that the core drill cut evenly. It has been demonstrated that if a core barrel cuts evenly an excellent core is produced. It is an object of this invention to provide a core drill of the character mentioned which will cut a straight hole and will cut evenly. The core drill of my invention has been designed with careful consideration in an endeavor to provide a core drill which will produce an integral core.

I accomplish the above specified object of this invention by providing the core drill with a lower cutter head which supports cutting blades and roller cutters. I have found that these two types of cutting elements combined as described hereinafter are effective in drilling a straight hole and in cutting evenly.

It is accordingly another object of this invention to provide a core drill with a cutter head having cutting blades and roller cutters which comprise the cutting elements thereof.

Other objects and advantages of the invention will be made hereinafter.

Referring to the drawing in which I illustrate a preferred form of the invention,

Fig. 1 is a vertical sectional view of a core drill having the features of the invention.

Fig. 2 is an enlarged section of the cutter head of the invention.

Fig. 3 is a section taken on the line 3-3 of Fig. 2.

Fig. 4 is an elevational view of Fig. 2 taken substantially as indicated by the arrow 4 of Fig. 2.

Referring in detail to the drawing and particularly to Fig. 1, the core drill of the invention has a core barrel 11. This core barrel 11 consists of an inner core retainer tube

12 and an outer shell 13. Formed integrally with the outer shell 13, at the lower end thereof, is a connector portion 15 having an externally threaded projection 16 to which a cutter head 17 is secured. The connector 15 is provided with internal threads 19 above the cylindrical projection 16, by means of which the lower end of the tube 12 is attached to the shell 13. The upper end of the shell 13 is attached to a coupling 20 which is threadedly secured to a head 21. The upper end of the tube 12 is threadedly secured to the coupling 20 as indicated at 22. Threadedly secured inside the tube 12 a slight distance below the coupling 20 is a plug 24 having a tube 25 extending upwardly therefrom, this tube 25 extending partly through a central opening 26 provided by the head 21. Openings 27 are provided in the tube 12 above the plug 24. These openings are provided for the purpose of conducting lubricating fluid such as rotary mud from the passage 26 of the head 21 to an annular space 28 formed between the tube 12 and the shell 13. The connector 15 is provided with fluid outlet passages 29 which connect to the lower end of the annular space 28. Lubricating fluid is supplied to the cutter head 17 through these passages 29.

An important part of my invention is embodied in the cutter head 17 which is shown in detail in Figs. 2 to 4 inclusive. Referring to these figures, the cutter head has a core opening 32 formed therethrough. This core opening 32 is enlarged at 33 to receive a core catcher 34. The core catcher 34 is secured in the enlargement 33 by the lower end of the threaded projection 16 of the connector 15 which is secured into an upper threaded end 35 of the core opening 32. It should be noted that the core opening 32 is aligned with and is connected to a core receiving chamber 36 provided by the core barrel 11. Formed at the lower end of the cutter head 17 are teeth 38 which are annularly arranged around the lower end of the core opening 32.

Extending upwardly from the cutter head 17 and preferably formed integrally therewith are cutting blades 39. In the preferred form of the invention I provide two diametrically opposed blades 39, but if desired I may

provide a greater number. The blades 39 extend from the lower end to the upper end of the cutter head 17. The lower ends of the blades 39 are provided with cutting edges 42. The cutting edges 42, as shown best in Fig. 4, may be curved in a concave fashion so that outer portions 43 are somewhat above the inner portions of the cutting edges 42.

Extended outwardly from the cutter head 17 are pins 45. These pins are formed integrally with the cutter head 17 and are arranged diametrically opposite each other and substantially centrally between the blades 39. This is clearly shown in Fig. 3. As shown best in Fig. 2, the pins 45 extend outward and upward. Carried by the pins 45 are roller cutters 46 having longitudinal teeth 47. The outer faces of the roller cutters 46 may be slightly conical. Placed between the cutter head 17 and the roller cutters 46 are inner wear plates 49 which rest partly in annular recesses 50 of the cutter body 17 and partly in annular recesses 51 formed on the inner faces of the roller cutters 46. For the purpose of retaining the roller cutters 46 on the pins 45, I provide retainers 54. The retainers 54 are provided with inner sockets 55 into which the outer ends of the pins 45 extend. The outer faces of the roller cutters 46 are provided with recesses 56 in which outer wear plates 57 are placed. These wear plates 57 are adapted to take the wear between the roller cutters 46 and faces 59 of the retainers 54. The retainers 54 are provided with arcuate channels 58, which are shown best in Figs. 2 and 4, through which the peripheral parts of the roller cutters 46 pass.

The upper parts of the retainers 54, as shown best in Figs. 2 and 4, are provided with upwardly extending arms 60 which are separated by spaces 61. As illustrated in Fig. 2, the cutter head 17 is provided with indentations 63 into which the inner parts of the arms 60 extend, these indentations serving as a bracing means for the arms, preventing them from being spread. Projecting outwardly from the cutter body 17 are ears 65. These ears 65 extend between pairs of indentations 63 and into the spaces 61 provided between the arms 60 of the retainers 54. Extending through openings formed in the arms of each retainer 54 and each ear 65 is a locking means in the form of a rod 66. Each rod 66 is riveted at its opposite ends as denoted at 67 in Fig. 4. The rods 66 serve the purpose of securing the retainers 54 to the cutter head 17.

In order that the outer parts of the blades 39 operate on the same plane as the roller cutters 46, it is necessary to form the cutting edge 42 as illustrated in Fig. 4. When the core drill is in operation, as illustrated in Fig. 1, the blades 39 and the roller cutters 46 cooperate to remove an annular area of material so that a central core 70 extends up-

wardly through the core opening 32 and into the core receiving chamber 36.

I have found from practice that the coaction of these two types of cutters produce a very straight hole and cut rapidly. The blades 39 have a cutting action which is likened to attrition whereas the roller cutters 46 roll over the bottom of the hole having a somewhat percussing action. The roller cutters provide the bottom of the hole with radial extending ribs which are separated by channels and the blades 39 cut these radial ribs as they are formed. It is believed that it is because of this type of cutting action that the operation of the core drill is very smooth. The roller cutters 46 have an extensive cutting surface and will have a very long life. The cutting edges 42 of the blades 39 will have a long life because of the fact that they do not operate on a smooth surface, but on a corrugated surface. The roller cutters 46 have a reaming action on the hole and therefore true the hole as it is drilled.

The features of the invention as heretofore pointed out are accomplished by the provision of the cutting blades 39 and the roller cutters 46.

I claim as my invention:

1. In a core barrel, the combination of: a barrel; a cutter head attached to the lower end of said barrel, said cutter head having a core opening concentric with the axis of rotation of said barrel and connected with the interior thereof; blades extending outwardly from said cutter head; and roller cutters carried by said cutter head, said roller cutters and said blades being adapted to cut the bottom of said hole along the same concentric path of travel.

2. In a core barrel, the combination of: a barrel; a cutter head attached to the lower end of said barrel, said cutter head having a core opening concentric with the axis of rotation of said barrel and connected with the interior thereof; blades extending outwardly from said cutter head; and roller cutters carried by said cutter head, said roller cutters being placed to follow in the path of said blades so as to cut on the bottom of the hole in back of said blades.

3. In a core barrel, the combination of: a barrel; a cutter head attached to the lower end of said barrel, said cutter head having a core opening concentric with the axis of rotation of said barrel and connected with the interior thereof; blades extending outwardly from said cutter head; pins extended outwardly from said cutter head; roller cutters rotatably carried by said pins; ears extending from said cutter head; retainers for holding said roller cutters on said pins, said retainers having arms extending on each side of said ears; and rods extending through said arms and said ears.

4. In a core barrel, the combination of: a

barrel; a cutter head attached to the lower end of said barrel, said cutter head having a core opening concentric with the axis of rotation of said barrel and connected with the interior thereof; blades extending outwardly from said cutter head; pins extended outwardly from said cutter head; roller cutters rotatably carried by said pins; ears extending from said cutter head above said pins; retainers for holding said roller cutters on said pins, said retainers having arms extending on each side of said ears; and rods extending through said arms and said ears.

5. In a core barrel, the combination of: a barrel; a cutter head attached to the lower end of said barrel, said cutter head having a core opening concentric with the axis of rotation of said barrel and connected with the interior thereof; teeth carried by said body, said teeth surrounding the lower end of said core opening; blades extending outwardly from said cutter head, said blades being adapted to scrape the bottom of the hole; and roller cutters carried by said cutter head, said roller cutters being placed so as to cut on the bottom of said hole.

6. In a core barrel, the combination of: a barrel; a cutter head attached to the lower end of said barrel, said cutter head having a core opening concentric with the axis of rotation of said barrel and connected with the interior thereof; teeth carried by said body, said teeth surrounding the lower end of said core opening; blades extending outwardly from said cutter head; pins extended outwardly from said cutter head; roller cutters rotatably carried by said pins, said roller cutters and said blades being adapted to cut the bottom of the hole; and means for holding said roller cutters on said pins.

40 7. In a core barrel, the combination of: a barrel; a cutter head attached to the lower end of said barrel, said cutter head having a core opening concentric with the axis of rotation of said barrel and connected with the interior thereof; teeth carried by said body, said teeth surrounding the lower end of said core opening; blades extending outwardly from said cutter head; pins extended outwardly from said cutter head; roller cutters rotatably carried by said pins; ears extending from said cutter head; retainers for holding said roller cutters on said pins, said retainers having arms extending on each side of said ears; and rods extending through said arms and said ears.

45 8. In a core cutter, the combination of: a cutter head; blades formed on said cutter head, said blades being adapted to scrape the bottom of the hole; pins extending outwardly from said cutter head; roller cutters rotatably carried by said pins, said roller cutters being adapted to cut the bottom of said hole; ears extending from said cutter head; retainers for holding said roller cutters on

said pins, said retainers having arms extending on each side of said ears; and rods extending through said arms and said ears.

9. In a core barrel cutter head construction, the combination of: blades adapted to 70 scrape the bottom of the hole; and rotary cutters adapted to cut corrugations in the bottom of said hole in the path of said blades.

10. In a core barrel cutter head construction, the combination of: blades associated 75 with said head, said blades being adapted to scrape the bottom of the hole; pins extending outwardly from said head; roller cutters rotatably carried by said pins, said roller cutters being adapted to cut the bottom of 80 said hole; ears associated with said head; retainers for holding said roller cutters on said pins, said retainers having arms extending on each side of said ears; and rods extending through said arms and said ears. 85

11. In a core barrel cutter head construction, the combination of: a body; pins extending outwardly from said body; roller cutters rotatably carried by said pins, said roller cutters being adapted to cut the bottom of 90 said hole; ears associated with said head; retainers for holding said roller cutters on said pins, said retainers having arms extending on each side of said ears; and rods extending through said arms and said ears. 95

In testimony whereof, I have hereunto set my hand at Los Angeles, California, this 30th day of October, 1926.

JOHN T. PHIPPS.
